(57) **CLAIM**

The ornamental design for an optical device mount, as shown.

DESCRIPTION

FIG. 1 is a perspective view of an optical device mount showing our new design having a scope-holding element in a first position.

FIG. 2 is a front elevation view of the optical device mount of FIG. 1.

FIG. 3 is a rear elevation view of the optical device mount of FIG. 1.

FIG. 4 is a right elevation view of the optical device mount of FIG. 1.

FIG. 5 is a left elevation view of the optical device mount of FIG. 1.

FIG. 6 is a top plan view of the optical device mount of FIG. 1.

FIG. 7 is a bottom plan view of the optical device mount of FIG. 1.

FIG. 8 is a perspective view of the optical device mount of FIG. 1 with the scope-holding element in a second position.

FIG. 9 is a front elevation view of the optical device mount of FIG. 8.

FIG. 10 is a rear elevation view of the optical device mount of FIG. 8.

FIG. 11 is a right elevation view of the optical device mount of FIG. 8.

FIG. 12 is a left elevation view of the optical device mount of FIG. 8.

FIG. 13 is a top plan view of the optical device mount of FIG. 8; and,

FIG. 14 is a bottom plan view of the optical device mount of FIG. 8.

The broken lines depict portions of the optical device mount that form no part of the claimed design.

1 Claim, 8 Drawing Sheets
